PRESSURE CORE DRILLING APPARATUS

John C. Stokes, Houston, Tex., assignor to Reed
Roller Bit Company, Houston, Tex., a corpo-
ration of Texas

Application May 11, 1942, Serial No. 442,399

4 Claims. (Cl. 255—72)

This invention relates in general to core drilling apparatus and has for its general object the provision of such an apparatus which will be capable of taking a core from a formation and removing the same to the surface of the ground under substantially the same conditions in which it existed in the formation.

In the ordinary core drilling methods and apparatus it is customary to use a drill which cuts an annular path and which is adapted to receive the core into its interior, after which the core is broken off and removed to the surface of the well. Such conventional apparatus, however, makes no provision for retaining or saving the gases or liquids which may be given off by the core as the pressure upon the core is reduced when the apparatus is withdrawn toward the surface of the ground.

It is therefore a primary object of this invention to provide an apparatus in which a core barrel which receives the core at the bottom of a bore hole will be kept substantially under bottom hole pressure while the core barrel and coring apparatus is being removed from the well.

Another object of this invention is to provide such an apparatus in which any gas or liquid given off by the core as the pressure within the core barrel is reduced may be saved for further analysis.

Another object of this invention is to provide such an apparatus in which provision is made for draining the slush from a drill stem on which the apparatus is carried so that when the drill stem is withdrawn from the well there will be no danger of having to pull a "wet" string.

Another object of this invention is to provide an apparatus of the character described in which after a core has been taken it may be hermetically sealed up so as to prevent it from losing any of its constituents or so as to prevent it from being contaminated by contact with foreign bodies while it is being removed from a well.

Other objects and advantages of this invention will become apparent from the following description taken in connection with the accompanying drawings wherein are set forth by way of illustration and example two embodiments of this invention.

In the drawings:

Fig. 1 shows a longitudinal cross section through the upper portion of a coring apparatus constructed in accordance with this invention.

Fig. 2 is a similar view illustrating the lower portion of the same apparatus.

Fig. 3 shows a transverse cross section taken along the line 3—3 of Fig. 2.

Fig. 4 shows a transverse cross section taken along the line 4—4 of Fig. 2.

Fig. 5 is a view on a reduced scale showing the apparatus illustrated in Figs. 1 to 4 inclusive when the parts are in position for taking a core.

Fig. 6 is a view similar to Fig. 1 but illustrating the parts in the position which they occupy after a core has been taken and prior to the time that the core has been removed from the apparatus, the core being hermetically sealed when the parts are in the position shown.

Fig. 7 is a view similar to Fig. 2 but showing the lower portion of the device with the parts in the position illustrated in Fig. 1.

Fig. 8 is a view similar to Fig. 1 but illustrating a slightly modified form of the invention.

Fig. 9 is a view similar to Fig. 2 but showing the lower portion of the apparatus illustrated in Fig. 8.

Fig. 10 is a view similar to Fig. 5 but showing the apparatus illustrated in Figs. 8 and 9 with the parts thereof in the position which they occupy during the taking of a core.

Fig. 11 is a view similar to Fig. 6 but showing the device illustrated in Figs. 8, 9 and 10 in the position which they occupy after the core barrel and the core contained therein have been hermetically sealed for withdrawal to the surface of the ground.

Fig. 12 is a view similar to Fig. 7 but illustrating the lower portion of the device shown in Fig. 11.

Referring first to the form illustrated in Figs. 1 to 7 inclusive, there is shown a drill collar 1 having a special sub 2 threaded to its lower end, this sub containing a flap valve 3 pivoted at 4 and adapted to close downwardly and to be urged downwardly toward closed position at all times by means of a spring 5. Access to this valve may be had by means of a plug 6 which is preferably welded into place after the parts have been assembled. Opposite the plug 6 and the mounting of the flap valve this sub is provided with another lateral opening in which is disclosed a check valve 7 adapted to prevent the escape of fluid outwardly through this lateral opening. This check valve is adapted to be inserted through the opening left by the removal of the plug 6, and threaded into place by means of a

wrench extending through said opening. While a core is being taken the lateral opening having the check valve 7 is additionally closed by means of a removable plug 8.

Secured to the lower end of the sub 2 is a core bit 9 which may be of any conventional construction having digging blades 10 and a core cutting head 11 therein. This core cutting head 11 has an upwardly facing internal shoulder 12 adapted to receive the lower end of a seated-in-head core barrel 13. This core barrel likewise may be of substantially conventional construction.

Mounted on the upper end of the seated-in-head core barrel is the core barrel head 14 having a passageway therein communicating between the interior of the core barrel and the exterior of the upper end thereof and controlled by means of a check valve 15 that is adapted to permit flow from the core barrel upwardly into the space between the core barrel and the drill collar but to prevent flow from the space between the core barrel and the drill collar downwardly into the core barrel.

The core barrel is suspended by means of a threaded fitting 16 threaded into the upper end of the core barrel head 14 as shown at 17 and having a lock nut 18 for holding it in place therein. The upper end of this fitting 16 is provided with a laterally extending flange 19 adapted to receive rubber bearing rings 20 carried within a shell 21 which is in turn threaded to the lower end of a socket member 22 adapted to receive the releasing tool presently to be described.

The socket member 22 has a socket formed in the upper end thereof with overhanging upper edges adapted to receive the automatic releasing connection the function of which will presently be explained. This automatic releasing connection 23 consists of a solid body at its upper end having downwardly extending flexible arms 24 each of which has an enlargement on its lower end with an outwardly turned hook-shaped part 25 adapted to enter and engage within the socket in the socket member 22. The amount by which this releasing connection can enter the socket in the member 22 is limited by means of stops 26 provided by the enlargements just mentioned on the lower ends of the arms 24. These stops 26 are also of such form that they flare slightly outwardly beyond the regular outer diameter of the remainder of the releasing connection 23.

Secured to the upper end of the releasing connection by means of a threaded connection 27 is a fitting 28 having a downwardly facing shoulder thereon by which a sealing ring 29 is held against the upper end of the releasing connection 23. Inasmuch as the fitting 28 is of somewhat smaller diameter than the releasing connection 23, this sealing ring 29 will provide an upwardly facing sealing surface.

Secured to the fitting 28 by welding 30 or the like and extending upwardly therefrom is a connector tube 31 having lateral openings 32 therefrom adjacent its lower end. This connector tube extends through a fitting 33 that is threaded to the upper end of the drill collar 1 and that has a counterbore 34 extending upwardly from its lower end and a groove in the bore adjacent the upper end thereof for the purpose of receiving a U-shaped sealing ring 35 adapted to prevent the flow of fluid upwardly through the fitting 33 around the connector tube 31.

On the upper end of the connector tube 31 is 75

a piston 36, the same being threaded to the upper end of the connector tube as shown at 37 and having lateral openings from its hollow interior to its exterior below the piston-like part thereof as shown at 38. These openings are normally closed on their inner ends by means of a sleeve valve 39 slidable in the piston 36 and this sleeve valve is urged upwardly at all times by means of the spring 40 that is disposed within the piston member and bears against the lower end of the sleeve valve.

The upper end of the sleeve valve is limited in its movement by contact with the fitting 41 that is threaded into the upper end of the piston and this fitting 41 is in turn threaded to receive the lower end of the hydraulic conductor tube 42.

Threadedly connected to the upper end of the fitting 33 is a tubular member or cylinder 43, this cylinder having an internal diameter of a size adapted to receive the piston 36 and having lateral openings therefrom as shown at 44 and 46 adjacent its upper end. The upper end of this cylinder 43 is threaded to receive a special substitute 45 having a bore therethrough with a groove at one point in the bore to receive a U-shaped packing ring 47, the bore and the packing ring being of such diameter as to in turn receive the upper end of the hydraulic conductor tube 42. The U-shaped packing ring is so disposed as to prevent the flow of fluid downwardly between the sub and the hydraulic conductor tube 42. The upper end of the sub 46 is preferably connected to a tool joint or some other portion of a drill stem, this being indicated by the numeral 48.

In the operation of the modification just described, the device is placed in a well with the parts in the position which they occupy in Figs. 1 and 2. The drilling then proceeds in the usual manner with the core barrel seated in the drilling bit 9 and having its upper end suspended by the various parts set forth including the automatic releasing connection. The automatic releasing connection is supported by means of the connector tube 31 that is suspended from the piston, the lower end of which engages the fitting 33 when the parts are in the position illustrated.

After the drilling has proceeded to the point where a suitable core has been received within the core barrel 13, a weighted plug is dropped into the drill stem and moves downwardly until it seats within the sleeve valve 39 as shown at 49. This plug may be weighted if desired by means of a rod 50 secured thereto by means of a pin 51. This plug serves to close the passage through the sleeve valve 39 and when fluid pressure is applied from above will cause this sleeve valve to move downwardly to the position shown in Fig. 6 so that fluid is then permitted to pass outwardly through the passages 38 in the piston into the annular space within the cylinder 43 and below the piston. Passage of fluid under pressure into this space will cause the piston to move upwardly to the position shown in Fig. 6. As the piston moves upwardly it will first pull the core barrel upwardly past the flap valve 3 whereupon this flap valve will close. As the piston moves further upwardly the automatic releasing connection will be drawn into the lower end of the fitting 33 and the flexible fingers forming this releasing connection will be moved radially inwardly so as to release the hook-shaped parts 25 from the socket on the upper end of the member 22. The core barrel will then drop back

downwardly until it rests upon the flap valve 3. Meantime the sealing ring 28 will have moved upwardly and come in contact with the shoulder at the upper end of the countersink 34 in the fitting 33. Thus the space within the drill collar which contains the core barrel will be hermetically sealed against the flow of any pressure fluid therefrom.

When the piston has moved upwardly to the position shown in Fig. 6 it will be observed that the passages 44 will have been uncovered so that slush flowing downwardly through the drill stem may pass outwardly to the exterior of the drill stem. Thus circulation may be maintained even though the fluid may not pass downwardly through the drilling bit.

With the parts in the position illustrated in Figs. 6 and 7 the device is then drawn to the surface of the ground. Thereupon the plug 8 may be removed and a suitable bleeder valve 52 connected to this opening and provided with means for opening the check valve 7 so that pressure fluid either gas or liquid may be bled from the interior of the drill collar. Such pressure fluid may be saved and analyzed so as to determine the content of gas or liquid within the core when it is taken under its pressure as it exists at the bottom of a hole.

After the pressure fluid has been thus bled off the apparatus may be disassembled and the core removed in the usual manner.

It will be seen that due to the fact that the opening from the interior of the drill stem is provided through the passages 38 in the piston and 44 in the cylinder 43, slush may drain from the drill stem during the time it is being removed from the well and there is no necessity for pulling a "wet" string of pipe.

Referring now to the modification appearing in Figs. 8 to 12 inclusive, the operation is very much the same as that heretofore described in connection with the form shown in Figs. 1 to 7 inclusive.

The lower portion of the apparatus is identical with that illustrated in Figs. 1 to 7 inclusive and the description thereof will for that reason not be repeated.

In this form, the fitting 28 is threaded directly into the core barrel head 14 and the automatically releasable connection 23 is entirely omitted. The sealing ring 28 which may be substantially the same as that illustrated in Fig. 2 is mounted directly on the upper end of the core barrel head 14.

Extending upwardly from the fitting 28 is a hollow piston tube 53 having lateral openings 54 therefrom adjacent its lower end. This tube passes upwardly through the fitting 55 that is secured to the upper end of the drill collar 1 and is secured at its upper end to a sleeve 56 which forms the body of a mechanical latching device whereby the parts are initially latched in the position shown in Figs. 8 and 9. This sleeve 56 has laterally opened slots 57 therein in which are pivotally mounted latching fingers 58 adapted when held in the position illustrated in Fig. 8 to engage within an annular groove 59 within the tubular member 60 that is carried on the upper end of the sub 55. These latching fingers 58 are normally held in the position illustrated in Fig. 8 by means of a sleeve 61 that is urged upwardly at all times by means of a spring 62 within the body 56.

Surrounding the lower portion of the body 56

is a packing ring 63 adapted when the parts are in the position illustrated to close the lateral openings 64 which extend through the walls of the tubular member 60. Bearing against the lower end of the body 56 is a washer 65 and between this washer and the upper end of the fitting 55 is interposed a coil spring 66 which serves at all times to urge the latching head 56 and the hollow piston tube 53 in an upward direction.

In operation, as previously described in connection with the first embodiment set forth, the parts are arranged in the positions shown in Figs. 8 and 9 and the core drilling proceeds in the usual manner.

After a core has been taken, there is dropped into the drill stem a tubular member 67 adapted to come into contact with the upper surfaces of the latching fingers 58 and move them to their released position as illustrated in Fig. 11. When this occurs the spring 66 is released and the tension thereon causes the upward movement of the latching head, the tubular member 53, and the core barrel.

As hereinbefore described, when the core barrel is moved upwardly past the flap valve 3 this flap valve will close thus preventing any flow of fluid from within the drill stem downwardly past the flap valve. The spring 66 is also of such construction that it will move the entire device upwardly until the sealing ring 28 engages the lower end of the fitting 55 forming a seal therewith and preventing the flow of any pressure fluid from within the drill stem upwardly through the fitting 55.

In the meantime, the packing 63 will have been moved upwardly away from the passages 64 so that any fluid within the drill stem may drain as the drill stem is raised, such fluid flowing through the openings 54 at the lower end of the tubular member 53 thence upwardly through the annular space within the fitting 55 and out through the passages 64.

When the device has been brought to the surface of the ground the fluid may be drained off as hereinbefore described and analyzed for the purpose of finding out just what the content of the core may have been when it was taken under the pressure conditions existing at the bottom of the well.

Illustrated in Fig. 12 more in detail is the valve 52 by which this pressure fluid may be drawn off. It will be seen that this valve includes a pin 68 operated by a handwheel 69 and adapted to be moved inwardly after the parts have been properly connected so as to unseat the check valve 7 and permit the pressure fluid to be withdrawn. The core may then be removed in the usual manner.

From the foregoing it will be appreciated that a device has been provided which is capable of carrying out all of the objects and advantages sought by this invention.

Having described my invention, I claim:

1. In a coring apparatus, a core drill, a core barrel within said core drill to receive a core cut thereby, a chamber above said core drill and carried thereby and adapted to receive said core barrel after the taking of a core, a piston connected to the upper end of said core barrel, valve means initially preventing the application of fluid pressure flowing through said device to said piston, and means for opening said valve to cause the application of fluid pressure to said piston to raise said barrel into said chamber, and means

for closing both ends of said chamber when said barrel has been raised thereinto.

2. In a coring apparatus, a core drill, a core barrel within said core drill to receive a core cut thereby, a chamber above said drill and carried thereby and adapted to receive said core barrel after the taking of a core, a piston connected to the upper end of said core barrel, valve means initially preventing the application of fluid under pressure flowing through said device to said piston, means for opening said valve to cause the application of fluid pressure to said piston to raise the said barrel into said chamber, means for closing both ends of said chamber when said barrel has been raised thereinto, and means for releasing said core barrel from said piston when said core barrel has been raised into said chamber and the ends of said chamber closed.

3. In a coring apparatus, a core drill, a core barrel within said core drill to receive a core cut thereby, a chamber above said drill and carried thereby and adapted to receive said core barrel

after the taking of a core, a spring for moving said core barrel upwardly into said chamber, means initially latching said core barrel down, and means for releasing said latching means to permit said spring to force said core barrel upwardly into said chamber.

4. In a coring apparatus, a core drill, a core barrel within said core drill to receive a core cut thereby, a chamber above said core drill and carried thereby and adapted to receive said core barrel after the taking of a core, means for forcing said core barrel upwardly into said chamber, means for preventing the operation of said first means until it is desired to have it operate, and means adapted to be passed downwardly through the drill stem for rendering said second means inoperative so as to permit operation of said first means, and means for closing both ends of said chamber when said barrel has been raised thereinto.

JOHN C. STOKES.
